HENRY H. HALL, OF BOSTON, MASSACHUSETTS.

Letters Patent No. 83,378, dated October 27, 1868.

IMPROVEMENT IN INDEXES.

The Schedule referred to in these Letters Patent and making part of the same.

To all whom it may concern:

Be it known that I, HENRY H. HALL, of Boston, in the county of Suffolk, and State of Massachusetts, have invented an improved Index or Tabular Guide for Indexes, of which the following is a full, clear, and exact description, reference being had to the accompanying drawings, making part of this specification, in which is illustrated one method of arranging my said index or tabular guide.

My invention has for its object to provide a ready means of indicating the location of any given name among any indefinite number of names, which shall serve as a guide to any name of a person, or an article in a catalogue, or an index of itself to any place, book, or article in a library or collection of articles, and also to places on maps, &c.; and my invention consists in a table composed of spaces for the reception of letters of the alphabet, and for numerals, the spaces being arranged in rows, and each space in one row containing a letter and a figure for its exponent, the value of denomination of the figure being different from that attached to the same letter in the adjacent rows, in order to avoid any undesirable repetition of a particular combination of letters, the said figures, when combined together, producing the whole or aggregate number corresponding to the name or requisite portion of name whose location is to be indicated.

To enable others skilled in the art to understand and use my invention, I will proceed to describe the manner in which I have carried it out.

In the said drawings is represented a sheet of card or Bristol-board, ruled into a number of vertical and horizontal rows, the number of spaces in each row corresponding to the number of letters and characters in the alphabet, the spaces in the upper horizontal row, and those in the left-hand vertical letter-row being occupied by the letters commencing with A, and alphabetically arranged therein, while each other horizontal and vertical letter-row contains all of the letters of the alphabet in their proper order, and the character "&," but does not commence with A. Each space, beside containing the letter, also contains one of the numerals, which serves as an exponent to denote the value of the letter.

To find the several figures which, when combined, constitute the whole or aggregate number necessary to indicate any given name, we look for the first letter of the Christian or surname of the person, or name of the place or thing, in the first or left-hand vertical letter-column, and the figure denoting its value, which we may (instead of carrying it in the mind,) write in pencil within a blank space set apart to the right, and intended as an erasible tablet. We then, in the same horizontal line as that of the first letter found, look up the other letters

in succession, and note down the figures corresponding thereto to the right of the figure representing the first letter found. The combination of numbers, or whole number, thus found, will indicate the location of such name in a book numbered on successive pages to receive the names of persons, places, or things.

To find the location in an index of the name J. B. Robb, we look for the letter J in the left-hand vertical letter-column, and find for its exponent the figure 2; then finding the letter B in the same horizontal row, we see that it is represented by the figure 2; next we find the figure 9 against the letter R, and the figure 6 against the letter O, and the figure 2 against the letter B, these five figures making the number 22,962, which indicates the location of the name or number (22,962) belonging to it in the index-book previously numbered.

The tabular guide may also be used independently of any index or catalogue, and may of itself (without a catalogue or register) serve the purpose of a correct index for libraries, museums, and cabinets, where books and various other articles are deposited.

Each book or article bearing a number, and being placed, in its numerical order, upon shelves, which are divided into sections, the book or article being readily found in its place, as soon as the number corresponding thereto is ascertained, by the combination of the several figures forming the exponents of the initials or first letters of its title. For instance, we wish to find a volume entitled History of England; we look in the left-hand vertical line for H, and then for I, S, E, and N, on the same horizontal row, and we find the number of the book is 92,377, which, when its location on one of the shelves is found, contains the book indicated.

It is evident that it will rarely be possible for two names of different persons, places, or things, to be represented by the same combination of letters, but such occurrence would not in any way be objectionable, as the duplicate would be in contiguous but distinct locations.

Besides its application to the purposes above enumerated, my invention will be of great assistance in the compilation of census-records, and may be employed for various other similar uses, without departing from the spirit of my invention.

What I claim as my invention, and desire to secure by Letters Patent, is—

The within-described index or tabular guide to indexes, consisting of the combination of letters and figures, substantially as and for the purposes set forth.

HENRY H. HALL.
